UNITED STATES PATENT OFFICE.

SOLOMON MARKS, OF CINCINNATI, OHIO.

DESIGN FOR A PATTERN FOR THE ORNAMENTATION OF SLATE-FRAMES.

SPECIFICATION forming part of Design No. 20,245, dated October 28, 1890.

Application filed September 15, 1890. Serial No. 365,095. Term of patent 14 years.

To all whom it may concern:

Be it known that I, SOLOMON MARKS, a citizen of the United States, residing at Cincinnati, in the county of Hamilton and State of Ohio, have invented and produced a new and original Design for a Pattern for the Ornamentation of Slate-Frames, of which the following is a specification, reference being had to the accompanying drawing, forming part thereof, which shows a side view of a slate showing my design.

The leading feature of my design consists in the representation of cobbler-stitching in line with the slate-frame and edge stitching at certain intervals along the cobbler-stitching extending over the outer edge of the slate-frame.

1 represents a slate-surface. 2 represents the surrounding frame. 3 represents holes in the frame, and 4 represents a binding.

As a pattern for ornamenting the slate-frame, I represent cobbler-stitching 5, extending in line with and around the frame, and edge stitching 6, extending at intervals along the cobbler-stitching to and over the outer 25 edge of the frame.

Having thus described my invention, the following is what I claim as new therein and desire to secure by Design Letters Patent:

The design for a pattern for the ornamentation of slate-frames, substantially as shown and described.

The foregoing specification of my invention signed by me this 8th day of September, A. D. 1890.

SOLOMON MARKS.
